UNITED STATES PATENT OFFICE.

HERBERT TOMLINS, OF LONDON, ENGLAND, ASSIGNOR TO THE ELECTRIC FOG-SIGNAL SYNDICATE, LIMITED, OF SAME PLACE.

FOG SIGNALING APPARATUS FOR RAILWAYS.

SPECIFICATION forming part of Letters Patent No. 605,361, dated June 7, 1898.

Application filed November 22, 1897. Serial No. 659,443. (No model.)

To all whom it may concern:

Be it known that I, HERBERT TOMLINS, decorator, of 100 Hammersmith road, London, W., England, have invented new and Improved 5 Fog Signaling Apparatus for Railways, of which the following is a full, clear, and exact description.

This invention relates to improvements in electrically-controlled train-operated automatic fog signaling apparatus for railways; and the improvements have for their objects to render the operation and firing of the fog signaling apparatus automatically dependent on the position of the semaphore-signal, to 15 guard against the danger of a misfire owing to a defective cartridge, to guard against two or more signals being fired in succession by the same train, and to improve the operation of the apparatus generally.

Reference is to be had to the accompanying drawings, forming part of this specification, wherein—

Figure 1 is a sectional elevation (with the casing removed) of the wheel-operated treadle mechanism, the treadle-lever being shown in the operative position. Fig. 2 is a modified form of Fig. 1. Fig. 3 is an elevation (with the casing removed) of the mechanism for operating the cartridge-holding disk. Fig. 4 is 20 an elevation (with the casing removed and viewed in the opposite direction to Fig. 3) of the firing mechanism just on the point of tripping a firing-hammer. Fig. 5 is a sectional plan view of the firing mechanism. Fig. 6 is 25 a side elevation (with the casing removed) of the entire apparatus. Figs. 7, 8, and 9 are detail views (to an enlarged scale) of one of the breech and firing mechanisms. Fig. 10 is a plan view of a modified form of support 30 for the firing-hammer. Fig. 11 shows a front elevation (with the casing partly in section) of a telltale instrument in the signal-cabin and a diagram showing the electrical connections of the whole apparatus. Figs. 12 and 45 13 are front and side elevations of an electrical switch.

A wheel-operated treadle A A' A' is arranged alongside the rail A², so that when permitted to rise, (for the purpose of bringing the fog signaling apparatus into use,) as shown in Figs. 1 and 2, the treadle will be in

position to be depressed by the flange of the leading wheel of a passing train.

C is a lever fast on the horizontal rock-shaft D of the fog signaling apparatus, the lever having a curved spring c fastened to it, which (when the fog signaling apparatus is in operative position) is adapted to bear upward against the treadle, so as to be depressed therewith. The spring c prevents the transmission of any violent shock to the apparatus and enables the apparatus to be so proportioned as to insure a sufficient angular motion being given to the rock-shaft D by a wheel-flange of greater or less depth, the depth of the flange varying according as the wheel is worn or not.

The shaft D passes beneath the rail and has fast upon it an arm E, which is normally retained in such upwardly-projecting position that when released it will act (either by its own gravity or by a spring e, or by both) to rock the shaft D and turn the cartridge-carrying disk F. The cartridge-carrying disk F is loose upon shaft D and is provided with peripheral ratchet-teeth, with which engages a pawl e', pivoted at e² to the arm E, the pawl being pressed into engagement by a spring e³. The disk F is turned to the extent of one tooth by each descent of the arm E, which besides rotating the disk F also raises the spring c of lever C into position to be acted on by the treadle A A'. The arm E is normally retained in the raised position by a latch-lever K, hereinafter described, and is only permitted to act as above described when fog signaling is necessary, the release of the arm E being then effected through electrical releasing mechanism operated conjointly with the semaphore-signal. This disk F has as 50 many double-barreled cartridge-chambers G (each barrel being adapted to hold a cartridge G') as there are ratchet-teeth in its periphery, the two chambers of each pair being perpendicular to the disk and arranged with their axes on the same radius, the several pairs being arranged in a circle, so as by the step-by-step rotation of the disk to come successively into firing position. By this radial arrangement as many double barrels or chambers can be got into a disk of given dimensions as though the barrels were single.

The firing of the charges is effected by a wiper h , carried by an arm H , fast to the shaft D , the arm H projecting radially of the disk in such position that the wiper h may be caused to act on the firing-hammer. This wiper is capable of being put in and out of operative position, as hereinafter described, and when the lever C is depressed by the treadle the wiper (if in operative position) trips a firing-hammer which acts on the breech mechanism of that cartridge-chamber which has been brought into the firing position by the previous descending movement of the arm E . By the same depression of the lever C the arm E is raised into position to act again, the pawl e' engaging with a fresh ratchet-tooth of disk F .

The wheel-operated treadle, as shown in Fig. 1, is composed of a bar A , having a parallel motion, and of two long levers A' , downwardly inclined from each end of the bar. In order to insure parallel motion of the bar A , it is coupled to links a of equal length, pivoted on a supporting-plate B , and it is operated by the depression of one or other of the levers A' by the wheel-flange, the ends of the bar A being for this purpose coupled to the levers $A' A'$ by pin-and-slot connections $a' a^2$, the levers A' being pivoted at $a^3 a^3$ to the supporting-plate B and being also guided laterally by the pins a' , passing through slots $b b$ in the vertical web of the base-plate B . The treadle-bar A and levers $A' A'$ move together, and they can be worked by a train passing either up or down the line. The treadle is kept in the raised position by springs B' , secured to the plate B and pressing against the under side of the treadle-bar A and levers $A' A'$, the motion of the treadle in the upward direction being limited by the pins a' and slots b in the plate B .

In the form shown in Fig. 2 the bar A is dispensed with and the levers $A' A'$ engage directly with one another by a tooth-like engagement consisting of a tooth a^5 on the end of one lever engaging in a suitably-formed notch a^6 in the end of the other lever, the levers acting directly on the spring c of lever C instead of through the horizontal bar A . As the fog signaling mechanism tends after a signal has been fired to reset itself in firing position so long as the semaphore-signal remains at "danger," it is necessary, in order to avoid more than one fog-signal being fired by the same train, to make the treadle of such length that before a wheel has quitted it the next following wheel will have come upon it, so that the treadle cannot rise while the train is passing. The strength of the springs B' is such that the treadle cannot be accidentally depressed, as by the weight of a person treading on it, but will only yield to the weight of a train.

The arm E , which turns the disk F and raises the lever C to operative position, is normally retained in readiness to so act by means of a self-engaging catch K , pivoted at k to the

arm E and engaging with a tooth k' , projecting from a fixed lug k^2 . The release of the catch K is effected electrically by the movement of the semaphore-signal to "danger," or it may be effected independently thereof in case of exceptional need by a manually-operated mechanical connection. The electrical release of the catch K is effected by the closure of the battery-circuit through an electromagnet k^3 by the movement of the semaphore-signal from the "all-right" to the "danger" position. The armature k^4 of the magnet k^3 is attached to one end of a lever k^5 , the other end of which bears underneath the catch K , so that when the armature is attracted by the magnet the catch is raised until it clears the tooth k' , thus allowing the arm E to fall and so rotate the disk F sufficiently to bring the next pair of barrels into firing position.

To release the catch mechanically in case of need, the lever k^5 is connected by a slotted link L to one arm of a bell-crank lever l' , the other arm being connected by a pull-wire l^2 to a lever (not shown) placed in any convenient position.

To support the catch K during the falling motion of the arm E , the side which rests on the end of lever k is made of such length that it is supported by the end of the lever during the complete falling motion of arm E . The upward motion of the catch is limited by a fixed pin k^6 , which also serves to limit the falling motion of the arm E by a lug k^7 on the catch coming in contact with the pin k^6 , the motion of the arm in the other direction being limited by a lug e^4 on the arm coming against the fixed lug k^2 . The catch engages by the action of its own weight, which may be reduced by the action of a spring, so as to reduce the work of the magnet to a minimum.

In case the disk F should be carried around too far spring-detents M are provided, which are pivoted to the arm E and press upon the cartridge-barrels G as teeth and act in opposition to a non-return pawl N , engaging with the teeth of the disk, so that the disk will always be returned to the accurate firing position. The detents M , being mounted on the arm E , move (during the fall of arm E) as one with the disk F , and therefore do not oppose its motion, the detents slipping past the barrels G when the arm E is raised by the train acting on the rock-shaft D through the treadle mechanism.

The breech ends of the double-barreled cartridge-chambers are closed by a hinged breech-block g , common to both barrels. Firing-pins g^2 (one to each chamber) pass through the breech-block and are yoked together by a bar g^3 , which is in position to be struck by a firing-hammer g^4 , pivoted in a bracket G^2 and acted upon by a spring g^5 , the arm g^{10} of the firing-hammer projecting in the path of the wiper h . The breech-block is hinged at g' and opens by swinging toward the circumference of the disk, the block being locked in the closed position by a spring-

catch g^6 , pivoted at g^7 and engaging with a lug g^8 , projecting from the breech-block. The tail end of the catch g^6 is prolonged, as shown, in order that it may be pulled back manually for the purpose of opening the breech for recharging. To facilitate the extraction of the spent cartridges, springs g^9 , fastened to the disk F , engage with the cartridges and when the breech-block is opened cause them to fly partly out, so that they can be easily extracted by hand.

The bracket G^2 , which carries the firing-hammer g^4 , may either be attached to the breech-block g , as shown in Figs. 4, 6, 7, 8, 15 and 9, or to a fixed support, as shown in Fig. 10. In the first case there would be a separate firing-hammer to each breech mechanism, the wiper h being common to all the hammers. When the wiper is in the operative position and caused to act by the depression of the treadle, it will trip that one of the firing-hammers which, together with the breech mechanism on which it acts, has been brought into the firing position by the previous descending movement of the arm E . In the second case there is only one firing-hammer, which is common to all the breech mechanisms, and the bracket G^2 , which carries the hammer, is attached to a fixed support in such a position that when the firing-hammer is tripped by the wiper h it will act upon the breech mechanism of that cartridge-chamber which for the time being is in the firing position. In order, in this second case, 35 to allow the wiper h to pass the projecting arm g^{10} of the firing-hammer when the arm E is moved in the opposite direction to that when it trips the hammer, the arm g^{10} of the hammer is knuckle-jointed, as at g^{11} , the joint 40 being rigid in one direction to enable the wiper h to trip the hammer, but capable of yielding in the other direction to allow the wiper to pass, the arm of the hammer being thereafter returned to its original position by 45 a spring g^{12} .

In order, in the first case described, to indicate which fire-hammer has been operated, a small curved arm g^{13} is pivoted to the breech-block at g^{14} and tends by a spring g^{15} to fly 50 out, as shown by dotted lines in Fig. 9, but is normally restrained by its end being passed under and engaged by an upturned lip g^{16} with the arm of the fire-hammer, which when tripped by the wiper h releases the lip g^{16} , 55 allowing the arm g^{13} to spring out of the dotted position of Fig. 9 and expose to view its end which was hidden by the hammer-arm, the end of the arm g^{13} being painted or otherwise made conspicuous.

60 The wiper h is made retractable by being fitted to slide in guides on the arm H , and when the semaphore-signal is moved from the "danger" to the "all-right" position the wiper h is so retracted and thus rendered inoperative by the action of a magnet h' , through 65 which the battery-circuit is closed by the said movement of the signal. The magnet h' is

mounted on the wiper-arm H , and its armature h^2 is jointed to a lever h^3 , pivoted at h^6 and coupled by a pin-and-slot joint h^7 to the lower end of the wiper h , so that when the magnet is energized the wiper is retracted. The wiper when thus retracted is held out of operative position by one arm h^{10} of a bell-crank lever being caused by a spring g^{11} to engage with a shoulder h^8 on the wiper. The retraction of the wiper is effected conjointly with the putting of the semaphore-signal to the "all-right" position, and when the wiper is thus retracted it will not act on the firing-hammer g^4 when the wiper-arm H is moved by a train depressing the treadle. The wiper will, however, be released by the other arm h^4 of the bell-crank lever coming in contact with the fixed pin h^5 , whereupon the wiper will be projected outward by a spring h^9 ; but this will not occur until after the wiper has been carried past the said firing-hammer g^4 , so that no fog-signal will be fired, (the semaphore being at "all right") although all the other movements of the fog-signal mechanism will take place and the wiper will be projected into operative position in readiness to act when next the semaphore-signal is put to "danger."

In order to concentrate the sound of the explosion in the required direction, the double barrel, when in the firing position, is in line with a stationary trumpet-mouth opening through the casing in which the apparatus is inclosed.

When it is required to bring the fog signaling apparatus into use, an electrical switch O in the signal-cabin is switched on by hand, so as to enable the various electrical circuits (necessary to work the fog signaling apparatus and also its telltale-indicator) to be automatically completed, on the one hand, by the movements of the semaphore-signal or of its operating-lever mechanism and, on the other hand, by the movements of the fog signaling mechanism itself. The hand-switch O having been thus closed, the energizing of the magnet k^8 of the fog signaling apparatus, which releases the catch K , and the energizing of the magnet h' , by which the retraction of the wiper h is effected, will then be automatically brought about by opposite movements of the semaphore-signal as follows: An electrical switch-lever v , pivoted at v' and placed in any convenient position, is adapted to be moved into contact with one or other of two terminals $v^2 v^3$ by being mechanically connected with the mechanism through which the semaphore-signal is operated, the switch v being so connected that when the hand-lever is moved to put the semaphore-signal to "danger" the switch v will be brought into contact with the terminal v^2 , whereby the circuit is completed through which the magnet k^8 is energized, this circuit remaining completed so long as the semaphore-signal remains at "danger."

The energizing of magnet k^8 causes the release of catch K and permits the arm E to fall and so partially rotate

the disk F to bring the next pair of cartridge-chambers to firing position and at same time raise the lever C into position to be actuated by the depression of the treadle, the fog signaling apparatus being thus in position to be operated by a passing train. When the semaphore-signal is lowered to the "all-right" position, the switch v makes passing contact with the terminal v^3 of the magnet h' , thus completing the circuit through which said magnet is energized. The energizing of magnet h' causes the retraction of the wiper h, thereby putting the firing mechanism out of action when the semaphore-signal is moved to the "all-right" position. The magnets k^3 and h' are both in connection with one pole of the battery, the other pole of which is in connection with switch v. The terminal v^3 is a spring set in such an oblique position, as shown in Figs. 12 and 13, that the switch v will pass behind it when the semaphore-signal is raised to the "danger" position, the then contacting surfaces being covered with insulating material, so that no circuit is thereby closed. As long as the semaphore-signal remains at "danger" so long does the switch v remain in the terminal v^2 . In order to avoid waste of electrical energy after the catch K has been raised, the circuit of magnet k^3 is automatically broken by means of a circuit-breaker carried by the arm E. This circuit-breaker may be formed by the switch p and a contact k^8 , as shown. The switch v and terminals v^2 v^3 may be placed in the signal-cabin and be operated by the hand-lever, which works the semaphore-signal, or they may be placed on the signal-post or in any other convenient position.

In order to indicate to the signalman that the cartridge-carrying disk F of the fog signaling apparatus has been carried round so as to bring a charged chamber into firing position and how many times it has been so moved, and likewise to inform him whether the firing mechanism is or is not in position to act, an electric telltale or register, such as shown in Fig. 11, is provided in the cabin, which is actuated by the closing of one or other of two electric circuits by a circuit closer in connection with the arm E. The telltale comprises an index-lever P, oscillated in one or other direction by one or other of two electromagnets Q R, the circuit of the one Q being closed by switch p, carried by arm E, making contact with terminal q of magnet Q when said arm reaches its highest position, whereby the index-lever P is moved to the position denoting that the treadle has been depressed, that the arm E has been raised, and that the wiper-arm H has been moved past a firing-hammer by the passage of a train. The circuit of the other magnet, R, is closed by switch p at terminal r of magnet R when the arm E reaches its lowest position, whereby the index is moved to the position denoting that the disk F has been moved to bring a charged chamber into firing position and

that lever C has been brought into position to be acted on by the treadle.

The switch p is electrically connected with the index-lever P, which is provided with circuit-breakers, whereby the circuit of the magnet (by which for the time being the index is moved) is broken just before the index reaches its extreme position, to which it is carried by its own momentum. The circuit-breakers consist of spring-brushes connected with the index-lever P, which rub upon the terminal contacts $q' r'$ of the electromagnets Q R, the contacts $q' r'$ being so arranged with regard to the index-lever that when the latter is in either of its extreme positions it is in electrical connection with the electromagnet, by which it will be moved to the opposite position when the circuit of that magnet is closed by the switch p.

When the index P is moved in the first-mentioned direction, denoting that the treadle has been depressed, it may either strike a bell mechanically or may in the course of its movement temporarily close at s s' the circuit of an electric bell to notify the signalman of the fact. The indicator denoting how many times the disk F has been moved is a dial T, bearing numbers which are consecutively exhibited at an aperture in the casing, this dial being rotated to the extent of one number (each time the index-lever is moved to the position indicating that the treadle has been depressed) by a spring-pawl t, carried by the index-lever and engaging with ratchet-teeth on the dial, a detent t', also carried by the index-lever limiting the movement of the disk, and a non-return pawl t² preventing retrograde motion of the dial when the index-lever is moved to the other position. An electric gong operated from the cabin would be provided at a suitable distance beyond the fog signaling apparatus for the purpose of signaling the train to go on again.

Having now particularly described and ascertained the nature of the said invention and in what manner the same is to be performed, I declare that what I claim is—

1. In the herein-described explosive signaling apparatus, a revolving cartridge-holding disk having pairs of cartridge-holding chambers or barrels arranged in a circle, the two members or barrels of each pair being on the same radius, in combination with a breech-block common to the two chambers or barrels, and hinged to swing outward toward the circumference when opened, firing-pins for the two barrels yoked together, and a firing-hammer adapted to act on both firing-pins substantially as specified.

2. In the herein-described explosive signaling mechanism the combination, with a revolving cartridge-holding disk provided with breech-closing and firing mechanisms as described, of a spring-projected retractable wiper for acting on the firing-hammer as described, the wiper being carried by an arm on a treadle-operated rock-shaft, an electromagnet

whereof the armature is connected to the wiper so as, when attracted, to retract the wiper from operative position, a switch connected to the signal-operating mechanism so as to close the circuit of the electromagnet when the signal is moved to "all right," and of retaining mechanism consisting of a lever-bolt caused to engage the wiper and retain it in the retracted inoperative position until, by the oscillation 10 of the rock-shaft by the depression of the treadle, the lever-bolt is tripped by contact with a fixed abutment and the wiper is permitted to resume its operative position in readiness for acting when next the signal is 15 put to "danger" substantially as specified.

3. In the herein-described explosive signaling apparatus the combination with a revolving cartridge-holding disk, of a gravity or spring operated pawl-arm, engaging with the 20 disk so as to give step-by-step motion thereto, and fast on a rock-shaft provided with another arm adapted when raised to be acted on by a wheel-depressed treadle, retaining mechanism consisting of a latch-lever engaging 25 with a catch for preventing the action of the lever, and of electromagnetic releasing mechanism for disengaging the latch on the closure of the magnet-circuit by a switch operated by the movement of the signal to "danger" 30 so that when the pawl-arm is thus permitted to act, the cartridge-carrying disk will be partially rotated to bring the next chamber to firing position and raise the other arm on the rock-shaft into position to be acted on 35 by the depression of the treadle as specified.

4. In the herein-described explosive signaling mechanism, the combination with a revolving disk having cartridge-holding chambers provided with breech-closing blocks, fire-pins and a spring-actuated hammer pivoted in position to act on the firing mechanism which is in firing position, of a radial wiper mounted on a rock-shaft concentric with the cartridge-disk so as to swing through an arc by the rocking motion of the shaft, the 40 wiper being mounted adjustably in such position that it may either be projected so as to act on the said fire-hammer, or be retracted so as to pass clear of the hammer without acting on it, according as the fog-signal is or is 45 not to be fired, as specified.

5. In the herein-described explosive signaling mechanism, the combination with each breech mechanism having its own firing-hammer, of an indicator consisting of a spring-plate pivoted to the breech-block in position to be swung beneath the fire-hammer of the mechanism to which it pertains, a spring tending 50 to swing such indicator-plate from beneath the hammer, and a lip on the indicator-plate adapted to be swung into locking engagement with the said hammer and to be released therefrom by the cocking of said hammer, substantially as specified.

Signed by me, the said HERBERT TOMLINS, 65 this 30th day of September, 1897.

HERBERT TOMLINS.

In presence of—

T. W. KENNARD,
L. TWINN.
